UNITED STATES PATENT OFFICE.

FARNUM F. DORSEY, OF WINCHESTER, MASSACHUSETTS, ASSIGNOR TO NORTH EAST ELECTRIC COMPANY, OF ROCHESTER, NEW YORK, A CORPORATION OF NEW YORK.

IGNITION APPARATUS.

1,314,131.

Specification of Letters Patent. Patented Aug. 26, 1919.

Application filed March 10, 1917. Serial No. 153,927.

To all whom it may concern:

Be it known that I, FARNUM F. DORSEY, a citizen of the United States, residing at Winchester, in the county of Middlesex and Commonwealth of Massachusetts, have invented certain new and useful Improvements in Ignition Apparatus; and I do hereby declare the following to be a full, clear, and exact description of the invention, such as will enable others skilled in the art to which it appertains to make and use the same.

This invention relates to ignition-apparatus such as is employed in connection with internal-combustion engines, and particularly with engines of motor-vehicles, which are operated at variable speeds.

The object of the invention is to produce simple and effective means for varying the time of operation of electric ignition-apparatus, either manually, or automatically, or in both manners. In electric ignition-apparatus it is common to employ a rotary circuit-controller by which the time of ignition is controlled, and to drive this circuit-controller in definite time-relation with the cycle of operations of the engine. The present invention relates particularly to the mechanical connections between the circuit-controller and the engine, whereby the time-relation in question is varied to change the time of ignition, and the invention consists in the novel features of construction and operation of the apparatus hereinafter described, as it is defined in the appended claims.

In the accompanying drawings Figure 1 is a side-elevation, partly in vertical section, of ignition-apparatus embodying the present invention; Fig. 2 is a side-elevation, on a slightly larger scale than Fig. 1, of a part of the mechanism including particularly the centrifugal timing-device; Fig. 3 is a plan-view of the apparatus shown in Fig. 1, but on a somewhat larger scale, with the upper part broken away; and Figs. 4 and 5 are, respectively, a front-elevation and a rear-elevation of the centrifugal timing-device.

The invention is illustrated as embodied in ignition-apparatus of the high-tension type, in which a rotary circuit-controller is employed which is arranged to control both the primary and the secondary circuits in the usual manner. As the circuit-controller

may be of an ordinary or suitable form, its construction is not particularly illustrated, but it is shown, by dotted lines in Fig. 1, as having the usual rotary elements 6 and 7 of the primary-circuit interrupter and the secondary-circuit distributer, these elements being mounted on and actuated by a vertical shaft 8 which turns in a bearing mounted in a casing 9.

The shaft 8 is provided, at its lower end, with a helical gear or worm-wheel 10 which meshes with and is driven by a helical gear or worm 11. The gear 11 is mounted on and actuated by a horizontal drive-shaft 12 which, in turn, is actuated by a shaft 13 connected with, or constituting a part of, the engine with which the ignition-apparatus is employed. In the apparatus specifically illustrated it will be understood that the shaft 13 rotates at the same speed as the crank-shaft of the engine, while the circuit-controller shaft 8 is rotated, through the helical gears, at one-half this speed. The shafts 12 and 13 are connected by a coupling 14 of the well known Oldham type, this coupling being adapted to accommodate itself both to lateral relative displacements of the shafts 12 and 13, and to relative longitudinal movements of these shafts.

One feature of the present invention resides in the provision for a change in the time of ignition by axial movement of one of the helical gears independent of its rotative movement. In the illustrated embodiment of the invention this axial movement is imparted to the driving-gear 11, by lengthwise movement of the shaft 12 on which it is mounted. For this purpose the shaft is journaled in a bearing-bushing 15 which is mounted to slide in a sleeve 16 forming a part of the casing 9. Thrust-washers 17, at the ends of the bearing-bushing, engage respectively the coupling 14 and the gear 11, so that the shaft and the gear are constrained to follow longitudinal movements of the bushing. It will be apparent that a slight longitudinal movement will be transmitted, through the gear 11, to the driven-gear 10, so as to result in a partial rotation of the shaft 8, whereby the angular position of this shaft and of the circuit-controller is varied for any given angular position of the shaft 12. The relative sizes of the parts are such that a sufficient adjustment may be produced in this manner by a

comparatively slight lengthwise movement of the shaft 12, such as may be readily accommodated by the coupling 14.

- The movement of the bearing-bushing 15 5 may be produced in any desired manner, or through any means whereby it is desired to control the time of ignition, but in the illustrated apparatus this movement is produced manually. For this purpose the sleeve 16 10 is slotted to receive a slide-block 18, which is secured to the bushing by dowels 19 and a screw-stud 20. Upon the stud a roller 21 is journaled, and this roller is controlled by a cam-plate 22, pivotally mounted on the 15 casing by means of a stud 23. The cam-plate is provided with an arm 24 which may be moved directly by hand, or connected with any suitable manually operable member. When the arm 24 is swung forwardly, i. e. 20 from left to right in Fig. 3, the shaft 12 is moved rearwardly, and this causes a partial clockwise rotation of the shaft 8 and the circuit-controller, while the movement of the arm 24 in the opposite direction 25 causes an opposite rotation of the circuit-controller. Assuming that the circuit-controller is driven in a clockwise direction, these movements result, respectively, in advancing and retarding the action of the 30 ignition-apparatus.
- The illustrated apparatus is provided with automatic speed-controlled means for varying the time of ignition, in addition to the manually-controlled means. For this 35 purpose the gear 11 is not fixed to the shaft 12, but is keyed to a sleeve 25 which is free to turn through a slight angle upon the shaft. The sleeve is integral with two oppositely-projecting arms 26, which support pivots 27 upon which two centrifugal weights 28 of crescent-like form are mounted, each weight being provided, near one end, with two ears 29 which embrace one of the arms 26 and receive the pivot thereon.
- In front of the parts just described a 40 plate 30 is mounted upon the shaft, this plate having a hub which is keyed so as to rotate with the shaft, and which is secured thereon by washers and a nut 31. The 45 sleeve 25 is confined against longitudinal movement on the shaft by engagement of its ends, respectively, with the hub of the plate 30 and with a shoulder upon the shaft. Each weight 28 is provided, near the end 50 opposite to that at which it is pivoted to the arm 26, with a stud 32 which projects forwardly through an opening 34 in the plate 30. The stud is provided with a roller 33 which cooperates with the edge of the 55 plate at said opening. The portion of the edge is engaged by the roller constitutes a cam, and the roller is maintained in engagement with this cam by means of a coiled tension-spring 37. One end of the spring 60 65 is hooked to engage the stud 32, being

seated in an annular groove therein, and the other hooked end of the spring engages a post 38 fixed on the plate 30. The cam-surface is concave in form, and so disposed that the portion engaged by the roller 7 33 when the parts are not in rotation, or are rotating at a comparatively low speed, is nearly normal to the length and the direction of pull of the spring 37, while the more remote portion 36 of the cam-surface rapidly 71 approximates a direction parallel with the line of pull of the spring. The plate 30 is rotated by the shaft 12, and by the pressure of the cam-surfaces against the rollers 33 the weights are caused to revolve. Through 80 the pivots 27 and the arms 26 the weights actuate the sleeve 25 and the gear 11. As the speed of rotation increases the centrifugal effect upon the weights causes them to swing outwardly, thus rotating the sleeve 85 25 relatively to the shaft 12, while the rollers move outwardly along the cam-surfaces. This movement is resisted by the springs 37, and the resistance of these springs varies in the direction of a rapid increase as the 90 rollers approach the outer parts of the cams. By suitable formation of the cam-surfaces, therefore, the centrifugal mechanism may be adjusted to advance the time of ignition in any desired proportion to the 95 speed of rotation.

The general arrangement of the cams, the cam-rollers and the springs is not claimed as a part of the present invention, but a feature of the present invention resides in 100 the novel and simple arrangement for assembling and retaining the parts of the automatic timer. Between each cam-roller and the corresponding spring a washer 39 is mounted loosely upon the stud 32, and this 105 washer retains the roller against endwise movement on the stud, while it is, in turn retained in place by the end of the spring. This spring-end, as before stated, is retained upon the stud by engagement with an annular groove therein, this engagement being securely maintained by the constant tension of the spring. When it is desired to 110 disassemble the parts, for any reason, this may be readily done by unhooking the 115 spring from the stud, whereupon the washer and the roller may at once be removed, and the plate 30 may then be readily removed from the shaft, thus affording access to the pivot-pins 27. These pins are shown as provided with heads which prevent the pins from escaping rearwardly, while they are retained against forward movement by their proximity to the rear surface of the 120 plate. When the plate has been removed, however, the pivot-pins may be withdrawn, thus permitting the removal of the weights 125 from the arms 26. The parts are assembled by the operations in the inverse order.

The invention is not limited to the em- 130

bodiment hereinbefore described and illustrated in the accompanying drawings, but it may be embodied in various other forms within the scope of the following claims.

The invention claimed is:

1. Ignition-apparatus having, in combination, a driven shaft; a circuit controller actuated thereby; a driving-shaft; helical gears connecting said shafts, one of said gears being loose on the corresponding shaft; an automatic timing device connecting the loose gear with its shaft and arranged to move the gear relatively to the shaft to vary the time of operation of the circuit-controller in accordance with the speed of rotation of the shafts; and means for moving the drive-shaft, and the gear carried thereby, axially, independently of but during rotation of the parts, to change the time of operation of the circuit-controller independently of the automatic timing-device.

2. Ignition-apparatus having, in combination, a circuit-controller; means, for actuating the circuit-controller, including a pair of intermeshing helical gears and a rotary member with which one of the gears is rotatively connected; means for changing the relative position of said gear and said rotary member to change the time of operation of the circuit-controller; and independent means for moving said gear axially, without change of said relative position, to change said time of operation.

3. Ignition-apparatus having, in combination, a circuit-controller; means, for actuating the circuit-controller, comprising a rotary member and a helical gear rotatively connected therewith but rotatable relatively thereto; means for rotating the gear relatively to said rotary member, to change the time of operation of the circuit-controller; and independent means for moving the gear axially to change said time of operation.

4. Ignition-apparatus having, in combination, a circuit-controller; a driven gear through which the circuit-controller is actu-

ated; a driving-gear meshing with the driven gear; a drive-shaft on which the driving-gear is mounted but relatively movable; an automatic speed-controlled device, 50 mounted on the drive-shaft, for moving the driving-gear relatively to the shaft to change the time of operation of the circuit-controller; and means for moving the shaft, independently of its normal rotation, together with the driving gear and said speed-controlled device, to change said time of operation independently of said device.

5. Ignition-apparatus having, in combination, a circuit-controller; a driven shaft 60 by which the circuit-controller is actuated; a helical gear on said shaft; a drive-shaft; a helical driving-gear, meshing with the beforementioned gear, mounted on, but rotatable with respect to, the drive-shaft; a centrifugal timing-device mounted on the drive-shaft and arranged to rotate the driving-gear relatively to said shaft, to change the time of operation of the circuit-controller according to the speed of rotation of the 70 drive-shaft; and means for moving the drive-shaft axially, together with the driving-gear and said timing-device, to change said time of operation independently of the speed of rotation of the drive-shaft.

6. In ignition-apparatus, an automatic timing-device comprising two relatively movable rotary members; a centrifugal weight movably connected with one of said members; a cam connected with the other of said members; a stud, on said weight, provided with a roller which engages said cam and which is removable over the end of the stud; and a spring, for controlling the weight, which has an interlocking engagement with said stud whereby the roller is normally retained thereon, the spring being disengageable from the stud but normally retained in engagement therewith by its resiliency.

FARNUM F. DORSEY.
